UNITED STATES PATENT OFFICE

EDWIN T. GRAY, OF NEW YORK, N. Y., ASSIGNOR TO W. H. S. LLOYD CO., OF NEW YORK, N. Y.

DESIGN FOR A WALL PANEL

Application filed April 27, 1929. Serial No. 31,031. Term of patent 3½ years.

To all whom it may concern:

Be it known that I, EDWIN T. GRAY, a citizen of the United States, residing at New York city, in the county of New York and State of New York, have invented a new, original, and ornamental Design for a Wall Panel, of which the following is a specification, reference being had to the accompanying drawing, forming a part thereof.

Figure 1 represents a wrought design of an

anaglyptically-produced wall panel showing my new design in elevation.

Figure 2 represents a longitudinal section, through the center of Figure 1.

Figure 3 represents a vertical section, taken through a central transverse line of Figure 1.

I claim:

The ornamental design for a wall panel, as shown.

EDWIN T. GRAY.
